INVENTOR:

BY J. Larrabee
his ATTORNEY.

UNITED STATES PATENT OFFICE

2,441,742

HARDWARE FOR OVERHEAD DOORS

William E. Wread, Los Angeles, Calif., assignor,
by mesne assignments, to Wread Overhead
Door Co., Los Angeles, Calif., a corporation

Continuation of application Serial No. 573,171,
January 17, 1945, which was substituted for
abandoned application Serial No. 364,412, No-
vember 5, 1940. This application December 3,
1945, Serial No. 632,381

3 Claims. (Cl. 16—129)

1

My invention relates to means for mounting overhead doors and the like, and particularly to the hardware by which an overhead door is pivotally and adjustably mounted upon a support so that it may be raised or swung about a horizontal axis or axes to an open position above the opening.

My invention is particularly adapted for use in hanging and mounting overhead doors for garage and store use, and an object of my invention is to provide a novel construction usable with overhead doors of light or heavy weight, and which will serve as a standard unit for garage doors throughout the entire residential field.

An object of my invention is to provide a novel set of hardware for overhead garage doors comprising a standard set or unit capable of a wide range of adjustments to adapt it to safe and efficient use, and in which the same spring counter-balance means may be adjusted as to obtain the desired leverage to provide proper operation with doors weighing up to 250 pounds or more.

An object of my invention is to provide a novel set of hardware for overhead doors which is simple, inexpensive and easy to assemble and install, and which may be made almost entirely of simple plate and tubular steel, the major parts of which may be manufactured by punch press operations.

Another object of my invention is to provide a novel set of hardware for overhead doors that may be manufactured and assembled at the factory and sold to the trade as a "unit" so that it can be installed by a carpenter of reasonable experience to obtain a perfect operating door.

Another object of my invention is to provide a novel set of hardware for overhead doors unencumbered by the difficulties heretofore encountered in the overhead counter-balance spring when mounted as to apply a pull on the roof timbers and side walls and which reduces to a minimum the dangers likely to result in the event of spring breakage.

Another object of my invention is to provide a novel set of hardware for overhead doors that will provide for a wide range of adaptability to varied requirements of installation, that may be easily and quickly adjusted and installed in the field by the average carpenter, and which after adjustment will be substantial and free from undesirable looseness or play.

A still further object of my invention is to provide a novel set of hardware for overhead doors

2

the parts of which may be manufactured in a factory, and which is adapted to mount a full line of doors including doors of the "no-head-room" or 4-point installation type and doors of the swivel or 2-point installation type.

A still further object of my invention is to provide a novel set of hardware for overhead doors which may be used in installing a 4-point door in a building having practically no head room above the top of the door or space between the building side walls and the edges of the door, the set including no guiding track, and being adapted for installation even though the distance between the side walls is 18 or 36 inches greater than the width of the door.

The invention resides in the parts and combinations of parts more particularly hereinafter described in detail and pointed out in the claims.

This invention is a continuation of application 20 Serial No. 573,171, filed January 17, 1945, now abandoned, which in turn was a substitute for application Serial No. 364,412, filed November 5, 1940.

Other objects, advantages and features of invention may appear from the accompanying drawings, the subjoined detail description, and the appended claims.

The accompanying drawings illustrate the invention in some of the forms I at present deem 30 preferable.

Figure 1 is a fragmental vertical sectional view through a closure member of the swivel type, and shows my novel hardware in elevation and the closure in its horizontal or raised position.

Figure 2 is a vertical sectional view through a closure member positioned in a "no-head-room" type garage, a fragment of which is shown, and shows my novel hardware of the 4-point installation type in elevation and in its raised or open 40 position, the dotted lines indicating the parts in their closed position.

Figure 3 is a side elevational view, partly in section and on an enlarged scale, of the rear pivot and supporting means of the 4-point installation of Figure 2.

Figure 4 is a view on an enlarged scale of the rear pivot when looking in the direction of the arrows on line 4—4 of Figure 2, certain parts being broken away to contract the view.

Figure 5 is a sectional view on an enlarged scale taken on line 5—5 of Figures 1, 2 and 3, and shows the pivot and supporting means journal.

Figure 6 is a fragmentary detail view illustrating an adjustable connection for the swivel type arms of Figure 1 similar to the adjustable con-

nection shown in Figures 2, 3 and 4 for the rear arms.

My invention relates particularly to hardware 1 for pivotally mounting and supporting a door or closure member 2 for an opening 3 in an enclosure such as a garage 4. The door 2 is pivoted or journaled about a horizontal axis or axes to permit of movement from a vertical or closed position to a horizontal or opened position.

Referring now particularly to Figure 1, it will be apparent that the door or closure member 2 may be mounted in any conventional opening or doorway 3 whether in a garage, aeroplane hangar or other building. The same type of construction is applicable with a wide range of door sizes.

The doorway 3 as shown is delimited at its top by a header 5 and at its sides by door jamb members 6. The door or closure member 2 is pivotally mounted at each of its sides to a side wall 7 of the garage or enclosure 4 and preferably to the studding 8 thereof. In its vertical closed position the door is positioned immediately behind the header 5 with its upper margin 9 extended adjacent to and in slightly overlapping contact with the inner lower edge of the header, as shown in Figure 2 in dotted lines. The header 5 thus forms a stop for the door in its movement to its closed position. When the door is moved to its open position the lower portion 10 of the door contacts the underside of the header 5 to prevent further inward swinging movement.

In Figure 1 I have shown the door 2 as being supported and journaled about a horizontal axis by the hardware 1 to illustrate the adaptability of my invention to a swivel type door. The identical hardware is provided at each side of the door, so that, for simplicity, only one side is illustrated and described.

The hardware 1 includes journal means 11, illustrated in section in Figure 5, comprising a hub 12 provided at one end with a flange 13 which is fixedly secured to a main supporting plate or base 14 by suitable means such as bolts 15. A main journal plate or door supporting member 16 is journaled intermediate its ends upon the hub 12 by means of a journal member 17 to the flange 18 of which the plate 16 is secured by bolts 19. A washer 20 is connected to the hub 12 by means of a stud bolt 21, and serves to retain the journal member 17 in place.

Adjustably secured to one end of the main journal plate 16 is a V-shaped tubular door supporting arm 22. Arm 22 has its base 23 adjustably secured and clamped to the outer or upper end 24 of the plate 16. The outer or free ends of the V-shaped arm 22 extend toward the door 2 and are adjustably connected thereto by telescoping into arm attaching brackets 26 in which they are fixedly secured by set screws 27. The attaching brackets 26 at their door engaging ends 28 are flattened and bent at an angle to the longitudinal axis of the engaged arm 22 so as to lie flush with the inner face of the door 2 to which each is secured as by a bolt 29.

The base or central portion of the V-shaped arm 22 is adjustably secured to the journal plate 16 by a clamp plate 30 held in locking position by bolts 31. Both the plate 16 and the clamp plate 30 are preferably provided with seat portions 32 which receive and embrace the arm base 23.

The spring counter-balance means indicated generally at 33 comprises a coil spring member 34 secured at one end by an eye bolt 35 to the sill or base 36 of the building or enclosure. The other

end of spring 34 is attached to an anchor bolt or post 37, adjustably secured to the inner or lower end 38 of the plate 16, that is, the end opposite to that to which the arm 22 is secured.

The inner or lower end 38 of plate 16 is preferably of the same construction as shown in Figures 7 and 8 of my copending application above referred to, being provided with a plurality of orifices 39. To the end 38 a transverse bar 40 is secured by bolts 41 which pass through orifices 42 in the bar and juxtaposed orifices 39 in end 38. The bolt 37 is secured in one of the orifices 42. It will be noted that the spaced orifices 39 in end 38 of plate 16 are arranged in rows along the edges of plate 16, and that the orifices 42 in bar 40 are so spaced relative to each other and the distance between the rows of orifices 39, that the distance between three orifices 42 equals the distance between the rows of orifices 39. This provides a wide selection in the adjustments to be obtained in positioning the bolt 37 relative to the axis of hub 12.

The spring 34 may be provided at either end with suitable tension controlling means. Such means may comprise the threaded bolt 43, illustrated in Figures 3 and 4, that swivels on post 37 and extends into an adjusting nut 44 secured to one end of spring 34.

From the foregoing it will be apparent that an overhead door of the swivel type may be mounted to close the opening into an enclosure, the mounting and journal means therefor being secured to the side walls of the enclosure and the supporting arms adjusted relative thereto and supporting the door thereon. It is also believed to be clear that the proper positioning of the door and of the hardware may be accomplished with a minimum of labor. The journal means 11, of course, will be mounted on the side walls of the enclosure at the proper height and horizontal spacing from the doorway as determined by the size of the door. In mounting the door the attaching brackets 26 may be loosely secured by the bolts 29 and with the free ends 25 of arm 22 extending therein. This will permit the arm brackets to be swiveled on the bolts 29 to obtain a multiplicity of offset angles for the arm 22 relative to the door and to the side wall. With the V-shaped arm 22 at the proper angle its base 23 may then be brought into engagement with seat 32 in plate 16 and clamp plate 30, and secured therein by tightening screws 31. The tightening of set screws 27 and bolts 29 then securely fixes the door and parts in adjusted position whereupon the tension of spring is adjusted by nut 44 to balance the door. In this construction the position of the anchor post 37 may, if desired, be determined at the factory for a door having the weight of the one to be mounted. Or, if preferred, the workman may easily change the location of the bolt on the job to obtain the desired leverage.

From the foregoing it will be apparent that the hardware may be mounted on a base plate *a* with the journal means 11 and spring eye 35 connected thereto. When so mounted the workman merely has to secure the "unit" to the enclosure side walls and connect the door to the arm to complete the installation. In shipping such a "unit" the arm 22 may be swiveled back upon the base plate *a* and the attaching brackets 26 fully telescoped on the free ends 25 to provide maximum compactness.

In the 4-point "no-head-room" type door installation shown in Figures 2, 3 and 4, use is made at the forward pivot of the journal means

11, here indicated by the reference character 11', which is identical to that heretofore described for the swivel type door installation with certain exceptions. The plate 16' of the journal means 11', corresponding to plate 16 on journal means 11, is devoid of the end 38 and its associated counter-balance means. Accordingly, and for the sake of brevity, the same numerals have been applied to like parts and further description thereof omitted.

In Figure 2, the forward door attaching arm 45 is provided at its inner end with a base portion 46 that extends substantially at right angles to the main portion of the arm and is clamped to the journal plate 16' by the clamp plate 39. Arm 45 has its outer end telescopically connected to the extensible portion 46' and is locked thereto by a set screw 47.

The rearward door attaching arm 48 has its inner end 49 bent upon itself in the form of a triangle to form a base portion 50 positioned in seat 32 in the journal plate 16 and the clamp plate 39. The inner extremity of arm 48 at the triangle is secured to the main portion of the arm by a clamp 51 and bolt 52 to give increased strength to the arm through bracing the main body portion in door raising and lowering operations. The outer end of arm 48 is telescopically received in the extensible portion 46'' which may be straight or bent, as shown, better to accommodate the front journal means. A set screw 53 holds the parts in fixed relation.

The extensible portions 46', 46'' of the forward and rearward arms at their ends adjacent the door are flattened, as at 54, and each is seated between the ears 55 of a journal collar 56 where it is held in place by a bolt 57. Each collar 56 is journaled upon a pin 58 lying parallel to the plane of the door and mounted thereon by clamps 59 and bolts 60. The clamps 59 are spaced upon the pin 58 and the journal collar 56 is positioned therebetween to prevent its displacement.

From the foregoing, it will be seen that the "offset" adjustment may be obtained for the door supporting arms by their angular adjustments between the ears 55 with the bolts 57 and 60 in a loosened condition. The tightening of the bolts fixes the angular relationship. It is also clear that in operation the arms 45 and 48 journal relative to their attaching pins 58 when the door is moved about its supporting hubs 12.

By using my novel hardware as hereinabove described in a 4-point type door, it is not necessary to provide the usual guiding track heretofore found in installations of this type. A more economical installation is thereby obtained. It should also be noted that in my construction the journal means for the door supporting arms may be attached directly to the building walls to provide a minimum obstruction within the building. Through extending the counter-balance spring downwardly from the journal rather than upwardly therefrom, I am able to use my hardware for installations where there is substantially no space between the edges of the door and the side walls. My hardware is also usable where the building wall upon which the journal means are mounted is spaced as much as 18 inches from the door edge.

My novel hardware enables me to make installations through a wide range of conditions using one standard set. Heretofore this could be accomplished only by making special parts to adapt the hardware to the requirements of the particular installation. As a result of its adapta-

bility my set of hardware for overhead doors may be formed at the factory as a "unit" usable for residential garages of customary widths and heights. By placing the counter-balance spring below the pivot adjustment thereof for different weights of doors is easily accomplished, as by moving the spring bar 40 away from the pivot or axle, and by moving the post 37 thereon.

By making the base portions 23 and 50 of the 10 arms slightly longer than the seat portions 32, a longitudinal adjustment of the arms in the seat 32 may be obtained to further aid in the universality of adaptation of the hardware.

As shown in Figures 2 and 4, the downwardly 15 extending supporting plate or base *a* may be provided to make a "unit" type construction for the rear hangar member of the 4-point installation and in practice I prefer to manufacture the construction as a "unit," the operating or main 20 journal plate 16 being journaled at the upper end of the anchor or base plate *a* and one end of the spring 34 of the counter-balance being connected between the lower end of the base or anchor plate and the transverse bar 40 or journal 25 plane 16. This provides a construction in which the parts may be applied to doors of all sizes and widths, and which may be used either as the rearward supporting means of a 4-point, "no-headroom" door installation or as the support of a 30 swivel type door installation and merely by changing the type of door attaching arms to be associated therewith.

In Figure 6 I have shown a fragmentary detail view illustrating the adaptation to the arms 35 26 of Figure 1 of an adjustable connection to the door 2, which connection is the same as shown for the arms 46' and 46'' in Figures 2, 3 and 4.

As a further step in the elimination of different types it is believed to be clear that the rear 40 supporting arms 48 may be used in place of the forward arms 45, if desired, and that this construction is adaptable to the branches of the forked arm 25 of the swivel type construction of Figure 1.

45 While the particular apparatus herein shown and described in detail is fully capable of attaining the objects and providing the advantages hereinbefore stated, it is to be understood that it is merely illustrative of the presently preferred 50 embodiment of my invention, and that I do not mean to limit myself to the details of construction or design herein shown, other than as defined in the appended claims.

I claim:

55 1. In a journal means for a swinging closure member including a supporting base; a plate journaled intermediate its ends to one end of said base; a seat extending transversely of said plate at one end thereof; a door attaching arm; clamp 60 means to clamp said arm in said seat; an arm attaching bracket telescopically connected to said arm and adapted to be adjustably connected to the closure member; and a counter-balance 65 means connected to the other end of said supporting base and to the other end of said plate.

2. In a door supporting means; a door supporting arm including telescopic members, one of which is provided with a base portion; pivot means including a main journal plate having a seat to receive said base portion; means to fixedly clamp said base portion in said seat; the other of said telescopic members being flattened at its free end; a journal collar having ears between 70 75 which said flattened portion is received; and

means to journal said collar to the door to be supported.

3. In an overhead door installation including pivot means adapted to pivotally connect the lower portion of the door to a side wall; operating means connected to said side wall in rear of said pivot means and to said door at substantially the mid-height thereof and comprising a plate journalled to said side wall; an arm extending from one end of said plate to said door at substantially the mid-height thereof; a bar connected to the other end of said plate and extending transversely thereof; and a spring connected to said bar and to a fixed point below the journal for said plate, the point of connection of said arm with said door, the journal for said plate and the fixed point for said spring

being in substantially a vertical plane through the axes of the journal when said door is moved to open position.

WILLIAM E. WREAD.
